UNITED STATES PATENT OFFICE.

SAMUEL E. HILLES, OF CINCINNATI, OHIO, ASSIGNOR TO THE SAMUEL C. TATUM COMPANY,
OF CINCINNATI, OHIO, A CORPORATION.

DESIGN FOR AN INKSTAND.

No. 40,125.

Specification for Design.

Patented July 6, 1909:

Application filed April 17, 1909. Serial No. 490,648. Term of patent 14 years.

To all whom it may concern:

Be it known that I, SAMUEL E. HILLES, a citizen of the United States, residing at Cincinnati, in the county of Hamilton and State of Ohio, have invented a new, original, and ornamental Design for Inkstands, of which the following is a specification, reference being had to the accompanying drawing, forming part thereof.

Figure 1 is a perspective view showing the design of ink-stands. Fig. 2 is a top plan view thereof.

1 represents the base of the ink-stand.

2 represents the shell of the ink-well projecting above the base.

3 represents the facets formed on the outer shell of the ink-well.

4 represents a dip-tube projecting into the shell of the ink-well.

I claim:—

The ornamental design for an ink-stand, as shown and described.

SAMUEL E. HILLES.
